CLAIM

The ornamental design for a test and measurement instrument for analyzing digital signals, as shown and described.

DESCRIPTION

FIG. 1 is a front perspective view of a test and measurement instrument for analyzing digital signals with a removable cover in place, showing our new design; FIG. 2 is a front perspective view thereof with the cover removed;

FIG. 3 is a front perspective view thereof with the cover hinged open;

FIG. 4 is a rear perspective view thereof with the removable cover in place;

FIG. 5 is a rear perspective view thereof with the cover removed;

FIG. 6 is a rear perspective view thereof with the cover hinged open;

FIG. 7 is a front elevation view thereof;

FIG. 8 is a rear elevation view thereof;

FIG. 9 is a top plan view thereof;

FIG. 10 is a bottom plan view thereof;

FIG. 11 is a left side elevation view thereof, and

FIG. 12 is a right side elevation view thereof.
